PNEUMATIC GUN

Alexander Boynton, San Antonio, Tex.

Application April 10, 1939, Serial No. 267,194

16 Claims. (Cl. 124—11)

My invention relates to machine guns using compressed air or other gas or gas forming substance as the propulsive means instead of gun powder as commonly used in machine guns.

An object of this invention is to provide a gun that enables the operator to quickly and accurately regulate the penetrating force of the bullets discharged from it and, at the same time, to control the rate of fire in order to control and subdue mobs and unlawful assemblies by first firing upon them with enough force to hurt and then increasing this force enough to kill if necessary. Such is believed to be an improvement upon the present practice of either firing harmless blank cartridges or maiming and killing with no alternative except to do one or the other.

Another object is to provide an air cooled gun that will not heat and that will discharge a greater number of shots without reloading than can be discharged from any other gun known to the art.

A further object is to provide a machine gun effective at short ranges which is more durable and cheaper to operate than any other known gun.

A still further object is to provide a gun that will accurately throw explosives with the least possible danger of detonation within the gun.

I accomplish the foregoing by means of compressed air or other gas employed to feed bullets out of a magazine, one at a time, and to force them successively against a yieldable ring at the breach of the barrel. Each bullet, as it engages the yieldable ring, will be stopped thereby until pressure fluid of sufficient value to force it through the ring builds up behind it. A reservoir in the gun stock is provided of sufficient capacity to store enough pressure fluid to accomplish the expulsion without allowing the pressure to become appreciably depleted before the expulsion is completed.

The rate of fire is determined by the rate that pressure fluid is supplied to the gun and the force with which the gun fires is regulated by the value of the pressure fluid used to operate it and by the resistance offered to the bullets by the yieldable ring which releases them into the gun barrel.

The construction and operation of a gun embodying the invention will appear from the following specification taken in connection with the drawings in which:

Fig. 1 is a top view of the gun.

Fig. 2 is a front end view of a partial assembly of the gun.

Fig. 3 is a side view of the gun.

Fig. 4 is a rear end view of the gun.

Fig. 5 is a longitudinal section of a portion of the gun showing all the moving parts and at

least a portion of all other parts, except the front sight assembly.

Fig. 6 is a transverse section on the line 6—6, Fig. 5.

Fig. 7 is a transverse section on the line 7—7, Fig. 5.

Fig. 8 is a transverse section on the line 8—8, Fig. 5.

Fig. 9 is a transverse section on the line 9—9, Fig. 5.

Fig. 10 is an isometric view of the forward plunger comprising an element of the invention. Fig. 11 is an isometric view of the air intake governor.

Similar characters refer to similar parts throughout the several views. Different portions of the same part are referred to by adding *a*, *b*, *c*, etc. (small letters), to the number employed to designate the part as a whole. A portion of a portion is referred to by adding a numeral to the letter following the characters designating the larger portion. Duplicated portions of any part are designated by priming the reference letter or numeral for the first duplication, and double priming the same for the second duplication.

Throughout the specification the direction "forward" is toward the muzzle, and "backward" is toward the breech and the barrel 2 will be assumed to be in the horizontal position.

With particular reference to Fig. 5, the stock 1, preferably a casting, having an internal chamber 1a, a throat 1d, a longitudinal bore 1d', and a short traverse bore 1d'', has a forward boss 1f within which an internally beveled surface 1n is opposed and oppositely inclined to surface 2c of barrel 2 to partially house the yieldable ring 3. The forward end of boss 1f is formed into a flange 1j behind which the annular trough 1k receives the internal flanges 4a and 4'a of the barrel holder half shells 4 and 4' respectively, the two half shells being held together as a unit by threaded engagement with the barrel holder retaining ring 5 having an internal flange 5b to reinforce the ring, protect the threads 2b, and provide stock for the wrench holes 5a.

A lug or key 2A within the key seat 2d of barrel 2 has a snug sliding fit within a slot or key way 1m by which key and key way the barrel 2 is restrained from rotating as the barrel holder shell is rotated in its engagement with the external threads 2b upon the barrel immediately forward of lug or key 2A. The front sight 20 and the rear sight 17, therefore, preserve their original alignment as the barrel is forced forward or backward by rotating the barrel holder 4—4'. It will be noted that key slot 1m is long enough to allow the barrel to travel forward or backward as the adjustment assembly 4—4'—5 is turned forcing the barrel inward or outward to adjust the ball release ring 3. Forward of threads 2b the barrel

is further secured and supported within an opening 14c through the connection 14.

The upper boss 6e is internally threaded for engagement with the lower boss 6e of the actuator housing 6, the bore 6e' being of the same diameter in perfect alignment with the bore 1a' and both of said bores being only slightly larger than the diameter of balls 23. The engagement between bosses 6e and 6e' is made air tight by means of washer or packing 1A.

Upwardly extending boss 6c on the actuator housing 6 is externally threaded for engagement with the neck 7b of the magazine 7, the engagement between boss 6c and neck 7b being made airtight by means of washer or packing 6A. The bore 6c', of slightly larger diameter than balls 23, registers with the lower end of bore 1c which gradually expands into the reservoir 1a which may be filled with balls 23.

Within the bore 6h' of rear extension 6h of the actuator housing, a rear plunger 8 has an easy working fit, the shoulder 8c of the plunger being resiliently urged in the direction of seat 6g by coiled spring 9 contacting cap 10 having ribs 10b through which are the wrench holes 10c. This cap is threadedly engaged over the rear end of extension 6h which it hermetically seals by closing upon washer 10A which may be of lead.

It will be noted that the forward portion of the plunger 8 is of reduced diameter at 8a and has a convex front end 8b which contacts the ball 23' to resiliently urge that ball (and each other ball which, in turn, assumes the same place) from backward movement in the bore 6d and tends to hold that ball directly under the one above it in the bore c' when the shoulder 8c engages upon the seat 6g.

Within the bore 6j' of the forward extension 6j the forward plunger 11 is resiliently urged forward to normally contact the air intake governor 12 by the force of spring 9A resting its rear end upon shoulder 6a and engaging its front end upon the head 11g which has a close working fit within the bore 6j'. It should be noted that rear end 11d of reduced diameter engages the ball 23' within a transverse trough 11c which trough conforms to the shape of the balls.

The circular extension 13a of guide screw 13 contacting washer 13A has a working fit within slot 11f for the purpose of preventing the plunger from rotating. The longitudinal trough 11e, which conforms to the surface of the balls, is of such depth as will prevent the ball 23' from engaging upon the rear end of plunger 11 when ball 23' is forced backward and ball 23'' starts downward as will be explained.

It will further be noted that the distance A between the point that ball 23' rests upon in the position shown and the center line of bore 6e' is exactly the same as the distance A', the travel of plunger 11 from the position in which it is shown until its shoulder 11a will engage upon the seat 6b, and that each of said distances is exactly the same as the distance A'' between the rear plunger 8 and the extension 10a.

An air intake governor 12, best shown in Fig. 11, fits within the forward end of housing 6 and is provided with the flange 12c which engages upon the shoulder 6f. It will be noted that the circular projection 12b has a loose fit within the central passage 11b through the plunger 11 and that the length of this engagement is somewhat less than the distance A' between shoulder 11a and seat 6b so that the passage 11b is unobstructed except by ball 23' when the plunger

11 is in its rearmost position. The circularly cut away portion 12d enables the feeding of air from the openings 12a into the passage 11b as fast as the projection 12b will permit when the plunger 11 is in its forward position. The feeding of air under pressure causes both plungers and the ball 23' to move backward until the ball 23', resiliently held between the plungers, is positioned directly over the upper end of opening 6e'.

Attention is directed to the fact that openings 12a are of somewhat larger cross sectional area than that of the passage 11b to provide that an ample supply of compressed air will be fed through them to discharge the bullets as will be explained.

The union clamp 16 has threaded engagement over the forward end of housing 6, the internal flange 16a engaging upon the union shoulder ring 15 having threaded engagement over the forward end of member 14. A leak proof engagement is obviously formed by tightening this union upon washer 16A which may be of lead or other soft metallic substance. As the union is tightened, portions of the washer are forced into a double series of depressions 6j upon the front face of forward extension 6j and 14d upon the rear face of connection 14. The washer thus answers the purpose of a key to firmly resist any rotation of connection 14 which rotation, if permitted, would disalign the front and rear sights. The opening 14c which snugly receives the un-tapered rear portion of gun barrel 2, therefore, affords a rigid forward support for the barrel.

The lower end of connection 14 is connected to a quick opening valve 22 having dial graduations 22a. This valve is shown connected to a flexible hose 24 which is in turn connected to a supply of compressed air or other gas.

The front sight 20 is slipped over the end of the barrel lodging against a shoulder, and set screw 21 engaging within a recess in the gun barrel secures the sight upon the barrel as shown.

The rear sight 17 has a square shank 17a intermediate of its two threaded portions of different diameters. This square shank fits snugly within an elongated rectangular opening 1c through the fin 1b, the elongated circular opening 1p being to accommodate the vertical movement of the enlarged threaded portion 17b of rear sight 17. By backing off nut 19 upon the portion 17c and screwing nut 18 to the right on portion 17b the sight 17 may be moved to the right. By a very similar adjustment nut 18 may be backed off and nut 19 screwed to the right in order to move sight 17 to the left. If the sight be moved to the right the adjustment is locked by nut 19, or if moved to the left the adjustment is locked by nut 18. The opening in the flanged end 19a of nut 19 is to receive the square shank 17a of sight 17 in case that portion should extend beyond the left side of the fin in adjusting the sight horizontally. The rear sight may be adjusted vertically by moving the square shank 17a upward or downward within the elongated rectangular opening 1c and tightening the nuts 18 and 19 upon the fin 1b as is apparent in Fig. 9.

The opening 1h of boss 1g is to receive a flexible rod upon which the gun may be mounted, the exact direction of aim being accomplished by rotating the gun upon this rod for horizontal direction, and by flexing the rod for vertical direction; the lower end of the rod being fastened to the floor of a motor driven vehicle such as a tank, truck, or tractor equipped with a compressor or reservoir of chemicals for the purpose of supplying compressed air or other gas under pressure

to operate the gun. The mounting may, of course, be stationary within trenches, buildings, or upon walls and the compressed air or other gas supplied by a pipe line connected to a battery of such guns placed at strategic points for defense.

The operation of the described embodiment is as follows:

The reservoir 1a being filled with a supply of bullets and compressed air under 1000 lbs. per square inch compression for example is assumed to be in the line 24. The handle 22b is turned until the indicator points at 4 half way opening the valve 22. Compressed air rushing through the opening 14a and shunted passage 14b explodes, so to speak, against the head 11g which has a close working fit within the bore 6f'. Plunger 11 is driven backward landing its shoulder 11a upon seat 6b, at the same time pushing ball 23' backward in the passage 6d to a point directly over the upper end of passage 6e' at which point the extension 10a of cap 10 stops the backward movement of plunger 8. The ball must stop exactly over the upper end of passage 6e' because, as previously stated, the three distances A, A', and A'' are exactly equal.

In its backward movement the plunger 11, just before it stops upon shoulder 6b, draws away from the projection 12b far enough to completely open the passage 11b. The 1000 lbs. of compressed air drives the ball through the passages 6e', 1d', and 1d'' to the dotted position 23a where it is momentarily arrested by the yieldable ball release ring 3. This ring is adjustably compressed between the bevels 1n and 2c so that 970 lbs. per square inch, for example, of compressed air will be required to force the ball through the passage thus restricted and into bore 2a. The engagement between the ball 23' (now in the position 23a) and ring 3 is leak proof.

Pressure entering through the throat 1d, narrower than the balls one way and much wider the other way, quickly builds up within the chamber 1a, the path of air flow into the chamber being through passage 11b, slot 11f, passages 6e', 1d', and throat 1d until the pressure in chamber 1a reaches 970 lbs. The ball 23' is then driven through the restricted passage in yieldable ring 3 and out of bore 2a in barrel.

It may be assumed that the springs 9 and 9A require 40 lbs. per sq. in. to begin compressing them from their position shown in Fig. 5 and that they build up 10 lbs. per sq. in. in compressing the distance A'. The springs are, therefore, assumed to be installed under a compression equal to four times the distance A'. Springs 9 and 9A, therefore, being returning the plungers 8 and 11 to their forward positions at 950 lbs. per sq. in. pressure, and complete the return at 960 lbs. pressure. The plungers 8 and 11 therefore will be returned to their original positions when the pressure acting against them is 10 lbs. less than the 970 lbs. assumed to be required to expel the ball.

The clearance between the extension 12b and the passage 11b is such as will allow sufficient air to quickly pass through it; thence through the slot 11f back of screw extension 13a; around ball 23'' (now moved to the position occupied by ball 23' in Fig. 5); and by the forward portion 8a of the plunger 8, to build up the other 10 lbs. making the 970 lbs. in chamber 1a necessary to expel the ball 23'. When the plungers return to their original positions as shown in Fig. 5, ball 23'' drops to the position previously occupied by ball 23' as above indicated. The

cycle described automatically repeats as long as balls and air under the assumed pressure are available.

Plungers 8 and 11 are stopped far enough apart by their respective seats to admit a ball between their proximate ends. In this manner each ball as it, in turn, assumes position between these plungers is held directly beneath the column of balls above it or permitted to roll slightly backward. This is to prevent the ball 23' (or any other ball which later assumes its position) from rolling forward in the bore 6d. If the ball should be allowed to roll forward (toward plunger 11) in the bore 6d the other balls in the column above it would settle and remain in contact with it. It could not then be driven backward by plunger 11 without slightly raising all the other balls in the column, and consequently, moving every other ball within the reservoir. The plunger extension 11d should, therefore, be long enough to hold the ball 23' from any possible movement away from the passage 6e'. Whatever slight clearance, in addition to the exact diameter of the balls, is allowed between the plunger ends, should be left between the ball 23' and the plunger extension 8a so that each ball at the base of the column, when it moves out of column, will move toward the opening 6e'.

When the ball 23' is driven backward by the plunger 11, as was explained, the ball 23'' above it moves slightly downward keeping in contact with ball 23' until the ball 23'' is stopped from further downward movement by longitudinal trough 11e into which it settles as it loses contact with ball 23'. The ball 23'' rides in this trough until the plunger 11 returns to the position shown in Fig. 5, when this ball drops to the position between the plungers, whence it follows the preceding ball in its path to the muzzle, as was explained.

It should be understood that, when the chamber 1a is filled with compressed air, pressure is also building up in the ball reservoir 1a. This pressure acts to force the ball 23'' down into place within the passage 6d as soon as the plungers have opened the place by assuming their normal positions as shown in Fig. 5.

A lubricant such as powdered graphite or a mixture of graphite and a liquid that will not disintegrate the yieldable ring 3 may be placed in the reservoir 1a with the balls or otherwise brought into contact with them and the opening through ring 3.

Obviously a wide range of pressures, spring forces, and ball release adjustments may be used, the pressure, spring force, and ball release adjustment assumed in the foregoing example being merely for illustration.

If it is desired to increase or decrease the rate of fire, the opening through the valve 22 may be properly increased or decreased. If the passage through ring 3 should wear or if it is desired to increase the pressure at which the bullets will be discharged and, of course, at the same time to increase the force of the bullets, the barrel may be moved rearwardly by turning barrel holder 5 to the left (assuming the threads to be right handed). This compresses the yieldable ring between surfaces 1n and 2c and thereby reduces the diameter of the passage through the ring, thus requiring more force to drive the balls through it, as is apparent. Screwing ring 5 in the opposite direction will, of course, accomplish the opposite result.

the adjustment unit, may be turned by hand to make quick changes in the force of the bullets. Another way to speed up the rate of fire is to reduce the space 1a. Manifestly, other conditions being equal, if this space be only half as great pressure will build up or drop within it twice as fast, thus doubling the rate of fire. It is also apparent that doubling the space 1a will produce the opposite result. In this connection it will be noted that the size of the space 1a and the extent of opening valve 22 may be used separately or together to increase or reduce the rate of fire. It is, therefore, apparent that by employing both means great extremes of speed or slowness of fire may be accomplished.

In connection with the rapid fire feature it should be further noted that with the assumed pressure and spring forces there is a comparatively slight pressure fluctuation in the chamber 1a, the gun firing at 970 lbs. and the plunger 11 going back to the cycle starting position shown in Fig. 5 upon relatively small drop in pressure. It will be realized that this drop in pressure within the chamber 1a will be almost instantaneous after each ball is discharged due to the rapid escape of air under high pressure through the open bore 2a until the escape is interrupted by another ball appearing in the dotted position 23a.

The difference between the force required to begin compressing the springs 9 and 9A and the force required to complete the compression the distance A determines the difference in pressures obtaining within the chamber 1a during the firing operation. If these springs are installed to compress the distance A at 5 lbs. per sq. in., retaining the same force of 40 lbs. to begin the compression, the gun will fire on a variation of 5 lbs. in the chamber 1a.

Reducing the differential between the maximum and minimum pressures in the chamber 1a not only increases the rate of fire, other conditions being equal, but also reduces the energy consumed in the firing operation.

In rapid fire the yieldable ring 3 will not be destroyed by heat due to the friction of the balls in rapidly flexing this member because of the frigid temperatures produced by the rapidly expanding air at that point.

Magazine shell 1 is preferably cast in two parts which may be welded together at 1d or otherwise hermetically joined. The shell so cast in two parts can be machined inside to provide a smooth surface for the balls to roll upon as they move downward. This smooth surface and the vibration produced by firing overcome the danger of the balls "bridging" or becoming impacted upon any peripheral unevenness that might result from the use of an unfinished casting. The balls will, therefore, be fed to the barrel regularly and without interruption during the firing operation.

Attention is called to the novel and important fact that this gun can be completely assembled or taken apart with a nail or rod of suitable size applied in holes 4b, 4'b, 5a, 10c, 12a, and 16b which holes may, for greater convenience, all be of the same size.

The foregoing specification, drawings, and appended claims are intended to set forth the invention as fully as may be done within the limits of a patent, with the understanding that many minor changes can be made in construction and arrangement of parts within the scope and purpose thereof.

What is claimed is:

1. A pneumatic gun comprising a stock, a barrel secured thereto, said stock and barrel having a passage for conducting bullets fired from the gun, means forming a pressure chamber communicating with said passage, a restriction in said passage, an actuator housing attached to the stock and having a passage communicating with the first mentioned passage, a source of pressure fluid connected to the actuator housing, and means within said housing for successively feeding bullets to said passages at a rate dependent upon the pressure rate of admission of pressure fluid to the housing.
15. 2. A pneumatic gun comprising a stock having a compression chamber therein, a barrel secured to said stock and having a bore for the passage of bullets therethru, said stock having a passage from said chamber to said bore, a restriction in said passage, an actuator housing attached to said stock and having a passage communicating with said first mentioned passage, a source of pressure fluid connected to said actuator housing, and means within said housing operable by the pressure fluid from said source for successively introducing bullets from within the actuator housing to the first mentioned passage.
3. In a pneumatic gun the combination of a stock having a passage adapted to conduct a bullet to be ejected under fluid pressure from the gun, a barrel, an enlargement in said passage to receive the end of the barrel and form an annular chamber between the barrel and stock, a resilient constriction forming a ring within said chamber, and means for adjustably positioning the end of the barrel within said enlargement to vary the extent of constriction produced by said ring.
30. 4. A bullet feeding mechanism for pneumatic guns comprising, a housing having a longitudinal bore therein, transverse offset passages entering said bore, spaced seats in said bore on opposite sides of said passages, opposed plungers within the bore adapted to engage said seats, means resiliently holding said plungers with their ends in spaced relation adjacent one of said passages to receive a bullet therebetween from one of said passages, and pneumatically operated means for moving the plungers longitudinally of the housing to move the bullet to the other of said passages.
45. 5. A bullet feeding mechanism for pneumatic guns comprising a housing having a bore therein, a transverse passage within said housing for conducting bullets into said bore, a transverse discharge passage from said bore, said discharge passage being offset from the first mentioned passage, and pneumatically actuated plunger means within the bore for successively transferring bullets to the discharge passage.
55. 6. A bullet feeding mechanism for pneumatic guns comprising a housing having a bore therein and a discharge passage transversely of the bore, means for admitting an actuating pressure fluid to the housing, means for feeding bullets into said bore, and a plunger operable by the actuating pressure fluid to move axially of said bore to move the bullets axially of the bore to said discharge passage.
70. 7. A pneumatic gun comprising an assembly including a stock having a compression chamber therein, a barrel secured to said stock and having a bore for the passage of a bullet therethrough, said stock having a passage between said chamber and said bore, an actuator housing attached to said assembly and having a passage
75. 75.

communicating with said first mentioned passage, a magazine attached to the actuator housing and adapted to supply projectiles to the interior of said housing, a source of pressure fluid connected to the housing, and means within the housing operable by the differential fluid pressure between said source and the first mentioned passage for successively introducing the projectiles to the bore of the barrel.

8. In a bullet feeding mechanism for pneumatic guns the combination of a housing having a bore and a discharge passage transversely of the bore, spaced plungers in said bore adapted to receive a bullet therebetween at a point in spaced relation with said passage, and means for supplying a fluid pressure to the interior of said bore to move the plungers and deliver the bullet within the discharge passage.

9. A pneumatic gun comprising a stock, a barrel secured thereto, said stock and barrel having a passage for conducting bullets fired from the gun, means forming a pressure chamber connected to said passage, an actuator housing having a bore and a discharge passage transversely of the bore, said discharge bore communicating with said first mentioned passage, spaced plungers in said bore adapted to receive a bullet therebetween at a point normally spaced from the discharge passage, and means for supplying a pressure fluid to the interior of the bore to move the plungers whereby the bullet is delivered to the discharge passage.

10. A pneumatic gun including a stock, a barrel removably secured thereto, a bore for bullets axially through said barrel, a yieldable ring in said stock at the breech end of said barrel, said ring being adapted to releasably hold bullets, each in succession of the other for expulsion through said barrel, a feeder passage for bullets in said stock, said passage being aligned with said bore, a reservoir for pressure fluid in said stock, a restricted opening in said stock, said opening communicating between said reservoir and said feeder passage, an actuator housing attached to said stock and having a transverse bullet feeder opening communicating with the bullet feeder passage in said stock, a magazine for bullets attached to said actuator housing, an opening for bullets out of said magazine, said opening being offset with said bullet feeder opening of said housing and both of said openings being large enough to allow for pressure fluid to flow past said bullets and into said magazine, an axial opening through said housing, said axial opening being transverse of said offset openings, a rear plunger in said axial opening, said plunger being urged forward by a spring, a forward plunger in said axial opening, said plunger being urged forward by another spring, so that a bullet impinged between said plungers will be moved backward through a portion of said axial opening into registration with the bullet feeder opening of said housing when said plungers are forced backward, a conductor means for pressure fluid connected to one end of said housing, a valve controlling pressure fluid in said conductor, said fluid being to force backward said plungers and the impinged bullet until the bullet moves in registration with said bullet feeder opening of said housing and to force the bullet through said feeder opening and into sealing contact with said yieldable ring and to force the bullet through said ring and bore after said pressure fluid has built up to a predetermined value within said reservoir, and means for restraining the forward movement of said first plunger so that another

bullet will be forced into said axial opening by pressure fluid in said magazine when said second plunger moves forward, the force of the spring urging said second plunger being somewhat greater than the force required to expel either of said bullets through said ring in order that said forward plunger will assume its extreme forward position and admit another bullet into said axial opening before each remaining of said bullets is expelled.

11. A pneumatic gun comprising a barrel having an axial bore for balls, a chamber communicating with said bore, a yieldable ring surrounding the bore at the breech end of said barrel, said ring being adapted to be sealably and releasably engaged by balls in succession of each other, a plunger housing having therein two plungers in spaced relation to each other, means for resiliently urging each of the plungers toward one end of the housing, a magazine attached to said housing, and having an opening for passage of balls therefrom, there being a passage from said opening communicating with said bore and having an off-set for balls through said housing, said off-set being adapted to temporarily restrain each ball in succession between said plungers, and a conduit for pressure fluid connected to one end of said housing, said housing and plungers being so constructed and arranged the pressure fluid entering through said conduit successively moves such restrained balls into a continuation of said passage to contact said ring and to force the balls therethrough and out of said bore when said fluid builds up to a predetermined value in said chamber.

12. A pneumatic gun including a stock having a reservoir and a passage communicating between said reservoir and the exterior of said stock, a barrel secured to said stock and having an axial bore for balls to pass therethrough, said bore having communication with said reservoir, a yieldable ring in said stock at the breech end of said barrel, said ring being adapted to be sealably and releasably engaged by balls each in succession of the other, an assembly including a plunger housing having therein two plungers in spaced relation to each other, each being resiliently urged forward by a spring, there being an opening for balls transverse of said housing, said opening having an offset therein, a magazine attached to said housing and having communication with said opening at its outer end, the off-set in said opening being adapted to temporarily restrain each ball in succession between said plungers, a conduit for pressure fluid connected to said housing, said assembly being so constructed and arranged as to successively move such restrained balls into the continuation of said transverse opening to contact said ring and to force said balls therethrough and out of said bore when said fluid builds up to a predetermined value in said reservoir, and means for varying the rate of admission of pressure fluid to said housing to control the rate of firing said gun.

13. A pneumatic gun including a stock containing a reservoir, a barrel secured to said stock and having an axial bore for balls, said bore having communication with said reservoir, a yieldable ring in said stock at the breech end of said barrel, said ring being adapted to be sealably and releasably engaged by balls in succession of each other, a plunger housing having two plungers axially disposed therein in spaced relation to each other, means for resiliently urging each of said plungers forwardly in the housing, a transverse opening for balls through said housing, a maga-

zine attached to said housing and having an opening communicating with said transverse opening and with said bore and said reservoir, there being an off-set in the passage for balls through said housing, said off-set being adapted to temporarily restrain each ball in succession between said plungers, a conduit for pressure fluid connected to one end of said housing to admit pressure fluid to move said plungers and successively move such restrained balls into a continuation of said opening to contact said ring and to force the same therethrough and out of said bore when said fluid builds up to a predetermined value in said reservoir, a manually operated valve in said conduit to regulate the rate of pressure fluid flow therethrough, and means for varying the rate of firing said gun by varying the rate of pressure fluid inflow thereto.

14. A pneumatic gun including a stock containing a reservoir, a barrel secured to said stock and having an axial bore for balls, said bore having communication with said reservoir, a yieldable ring in said stock at the breech end of said barrel, said ring being adapted to be sealably and releasably engaged by balls in succession of each other, a plunger housing having two plungers axially disposed therein in spaced relation to each other, spring means for urging each of said plungers forwardly in the housing, a magazine attached to said housing and having an opening for balls out of said magazine, said opening communicating with said transverse opening and with said bore, there being an off-set in the passage for balls through said housing, said off-set being adapted to temporarily restrain each ball in succession between said plungers, a conduit for pressure fluid connected to one end of said housing to admit pressure fluid to move said plungers and successively move such restrained balls into a continuation of said opening to contact said ring and to force the same therethrough and out of said bore when said fluid builds up to a predetermined value in said reservoir, and means for varying the force of said balls by compressing said ring so as to diminish the diameter of the opening therethrough.

15. A pneumatic gun including a stock containing a reservoir, a barrel secured to said stock and having an axial bore for balls, said bore having communication with said reservoir, a yieldable ring in said stock at the breech end of said barrel, said ring being adapted to be sealably and releasably engaged by balls in succession of each other, a plunger housing having two plungers axially disposed therein in spaced relation to each other, a spring urging each of the plungers

forwardly in the housing, there being a transverse opening for balls through said housing, a magazine attached to said housing and having an opening for balls out of said magazine, said opening communicating with said transverse opening and with said bore and said reservoir, there being an off-set in the passage for balls through said housing, said off-set being adapted to temporarily restrain each ball in succession between said plungers, a conduit for pressure fluid connected to one end of said housing to admit pressure fluid and move said plungers to successively move such restrained balls into a continuation of said opening to contact said ring and to force the same therethrough and out of said bore when said fluid builds up to a predetermined value in said reservoir, a manually operated valve in said conduit to regulate the rate of pressure fluid flow therethrough, means for varying the rate of firing said gun by varying the rate of pressure fluid inflow thereto, and means for varying the force of said balls by compressing said ring so as to vary the diameter of the opening therethrough.

16. In a gun, a housing, a stock, means for feeding bullets through a transverse opening in the housing to the breech end of a barrel connected to a stock, said bullets being fed in column formation through an opening communicating between said magazine and housing attached thereto, closure means for one end of said housing, a spring in said housing, said spring yieldably engaging a plunger slidable in the housing, means in said housing for limiting the travel of said plunger, an axial extension of said plunger, another plunger in the other end of said housing, said other plunger having an axial opening therethrough, means for varying the size of said opening in different positions of said plunger, another spring in said housing, said spring being adapted to yieldably urge said second plunger away from the first plunger, means for restraining said second plunger from rotation within said housing, pressure means connected to the other end of said housing for moving said second plunger, the end bullet of said column, and said first plunger to engage said first plunger with one of said means for limiting its travel when said end bullet is in registration with said transverse opening, means actuated by pressure fluid for expelling said end bullet from said housing through said opening, and means in said housing to engage the next bullet in said column between said plungers after each previous bullet has been forced from the housing.

ALEXANDER BOYNTON.
